UNITED STATES PATENT OFFICE.

JERMAH H. BRENNAN, OF BOSTON, MASSACHUSETTS.

DEVICE FOR TAPPING BEER.

SPECIFICATION forming part of Letters Patent No. 296,311, dated April 8, 1884.

Application filed November 3, 1883. (No model.)

To all whom it may concern:

Be it known that I, JERMAH H. BRENNAN, a citizen of the United States, residing at Boston, in the county of Suffolk and State of Massachusetts, have invented certain Improvements in Devices for Tapping Beer and other Barrels, of which the following is a full, clear, and exact description, reference being had to the accompanying drawings, making part of this specification, in which—

Figure 1 is a side elevation of a beer-faucet and bushing constructed in accordance with my invention. Fig. 2 is a longitudinal vertical section through the center of the same applied to the head of a barrel. Fig. 3 is a view of the removable screw-plug which contains the valve-seat. Fig. 4 is a view of the inner end of the stem or neck of the beer-faucet.

My invention relates to certain improvements in devices for tapping beer and other barrels, and has for its object to enable the valve and other parts contained within the bushing to be easily removed without taking the bushing out of the barrel-head, thus greatly facilitating the operations of cleansing and repairing the parts, and also avoiding the undue enlargement of the tap-hole, and consequent spoiling of the head of the barrel, which results from frequently removing and replacing the bushing; and my invention consists in certain details of construction and combinations of parts, whereby the desired results are attained in a simple and effectual manner.

In the said drawings, A represents the head 35 of a beer-barrel, within the tap-hole of which is screwed the tapering bushing B, provided with an external screw-thread, this bushing being intended to remain permanently within the head A. The rear portion, a, of the bushing, which projects beyond the inner surface of the head, is turned down smooth on the outside, and is provided with a series of perforations, b, forming a strainer through which the beer passes to the chamber c.

D is a removable cylindrical plug, which is provided with an external thread, d, which engages with a thread, e, on the inside of the portion f of the bushing, the plug D having square notches or recesses g in its front end 50 for the reception of the end of a suitable implement, by means of which the plug can be

turned in or out of the bushing, the latter being provided with a shoulder, 10, against which the plug is seated, as seen in Fig. 2. On the inner end of the plug D is formed an 55 annular seat, h, for the valve i, the stem k of which projects through a central aperture, l, in the plug D into a recess, m, in the front thereof, the inner portion of the stem k being of increased diameter, to afford a larger bearing-surface and reduce the wear on the parts.

Within the chamber c is placed a strong spiral spring, G, which is guided and maintained in its proper central position with respect to the valve i by means of a guide stud 65 or pin, n, projecting from the rear of the valve, and a similar guide-stud, p, arranged opposite thereto and projecting from the rear end of the chamber c toward the valve. The web or central portion, 12, of the plug D is provided 70 with a series of small apertures, q, arranged in a circle around the aperture l, these perforations q forming a second strainer, through which the beer flows when the valve i is forced back from its seat h against the resistance of 75 the spring G by a protuberance, r, at the center of the inner end of the stem s of the faucet H as the latter is screwed into the bushing. The stem s is provided at its rear end, 13, with an external thread, t, which engages with the 80 internal thread, e, of the bushing, and at the opposite end of the stem s, close to the shoulder u, is another externally-threaded portion, a', of slightly larger diameter than the portion 13, which engages with a corresponding thread, 85 b', on the inside of the mouth of the bushing B, at the outer edge of which is an annular groove, 15, for the reception of the shoulder u of the faucet, by which construction a tight joint is insured and the front end of the stem 90 of the faucet is firmly supported at both ends, as required, while by providing the stem s with a short thread, t, at its rear end and another short thread, a', of slightly larger diameter at its opposite end with a smooth non-threaded 95 portion between them, the necessity of cutting a thread along its entire length is avoided and the time required to screw it into the bushing greatly reduced.

The inner end of the faucet H is closed and 100 is provided with a series of small perforations, c', arranged in a circle around the protuber-

ance *r*, a third strainer being thus provided in the faucet itself, in addition to the two strain-
ers of the bushing, which insures the liquid
being freed from all particles of foreign mat-
ter.

5 It will be apparent that whenever it is re-
quired to cleanse the interior of the bushing
and parts contained therein, or gain access to
the same for repairs, it is simply necessary
10 to turn the plug *D* with a suitable wrench or
other implement until it is clear of the thread
e of the bushing, when it can be readily taken
out, together with the valve *i* and spring *G*, no
15 removal of the bushing *B* from the barrel-
head being required, and the wearing out of
the tap-hole, and the consequent spoiling of the
head of the barrel, heretofore caused by the
frequent removal and replacing the bushing
20 as heretofore, being thus entirely avoided, and
a saving in time and labor also effected. As
the faucet is unscrewed from the bushing, the
spring *G* will tightly close the valve *i*, thus
preventing any escape of the beer or gas, in
25 case it should be desired to remove the faucet
before the barrel is empty, and also keeping
the barrel air-tight.

I am aware that a bushing has been provided
with a valve adapted to be opened against the
30 resistance of a spiral spring by a faucet, as the
latter is screwed into the bushing; hence I
make no broad claim to such construction,
confining myself to the details of construction
and combination and arrangement of parts
herein specified.

35 What I claim as my invention, and desire to
secure by Letters Patent, is—

1. In a barrel-tapping device, the externally-
threaded bushing *B*, having at its inner end
the perforated chamber *c*, and provided with
40 an internal thread, *e*, and shoulder *10*, in com-
bination with the removable screw-plug *D*,
adapted to be inserted into and taken out from

the front end of the bushing, and having the
valve-seat *h* and a web, *12*, provided with a
series of perforations, *g*, arranged around the
45 central aperture, *l*, in front of the valve-seat,
the valve *i*, with its stud *n*, the spiral spring
G, and the stud *p*, projecting inward from the
rear end of the chamber *c*, and the faucet *H*,
adapted to be brought into contact with and press
50 back the stem of the valve *i* as it is screwed
into the bushing, the whole constructed and
arranged to co-operate substantially in the
manner and for the purpose set forth.

2. In a barrel-tapping device, the combina-
tion, with the bushing *B*, removable screw-
plug *D*, having a recess, *m*, in its front side,
and a series of perforations, *g*, the valve *i*, with
55 its stem *k*, projecting into said recess *m*, and
the spring *G*, of the faucet *H*, provided with
an external thread, *t*, and having its inner end
closed and provided with a protuberance, *r*,
surrounded by a strainer formed of a series of
60 perforations, *c'*, all constructed and arranged
to operate substantially in the manner and for
65 the purpose described.

3. In a barrel-tapping device, the combina-
tion, with the bushing *B*, provided with an
internal thread, *e*, and a second internal thread,
70 *b'*, at its mouth, of larger diameter, the remova-
ble screw-plug *D*, valve *i*, and spring *G*, of the
faucet *H*, having its stem *s* provided at its
rear end with a thread, *t*, and at the opposite
end with a shoulder, *u*, and a second thread,
75 *a'*, of larger diameter, with a smooth or non-
threaded portion between them, all constructed
and arranged to operate substantially in the
manner and for the purpose set forth.

Witness my hand this 30th day of October,
A. D. 1883.

JERMAH H. BRENNAN.

In presence of—

P. E. TESCHEMACHER,
W. J. CAMBRIDGE.
